US0D1096038S

(12) **United States Design Patent** (10) **Patent No.:** **US D1,096,038 S**
(45) **Date of Patent:** **** Sep. 30, 2025**

(54) **SCRAPER**

(71) Applicant: **MAYA TECHNOLOGIES LIMITED,**
Hong Kong (CN)

(72) Inventor: **Shanglin Yang**, Hong Kong (CN)

(73) Assignee: **MAYA TECHNOLOGIES LIMITED,**
Hong Kong (CN)

(**) Term: **15 Years**

(21) Appl. No.: **29/989,717**

(22) Filed: **Feb. 14, 2025**

(51) LOC (15) Cl. **07-05**

(52) U.S. Cl.

USPC **D32/46**

(58) **Field of Classification Search**

USPC D32/40-43, 45-46, 50-52; D8/90;
D4/116, 118

CPC A47L 13/16; A47L 1/08; B25G 3/38

See application file for complete search history.

(57) **CLAIM**

The ornamental design for a scraper as shown and described.

DESCRIPTION

FIG. 1 is a perspective view of a scraper showing my new
design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the scraper where the scraper
is in a first configuration of use;

FIG. 10 is a perspective view of the scraper where the
scraper is in a second configuration of use; and,

FIG. 11 is an enlarged view of portion 11 shown in FIG. 1.
The dash-dash broken lines in the drawings depict portions
of the scraper that form no part of the claimed design. The
dot-dash broken lines in the FIGS. 1 and 11 depict enlarge-
ment indications and form no part of the claimed design.

1 Claim, 11 Drawing Sheets
